CLAIM

The ornamental design for a cart for line striper, as shown and described.

DESCRIPTION

FIG. 1 is a isometric perspective view of the cart for lines striper, showing our new design, the broken line showing is for illustrative purposes only, and forms no part of the claimed design;

FIG. 2 is a top plan view thereof;

FIG. 3 is a bottom plan view thereof;

FIG. 4 is a left side elevational view thereof;

FIG. 5 is a rear elevational view thereof; and,

FIG. 6 is a front elevational view thereof.

Fig. 1**Fig. 2****Fig. 3**
